UNITED STATES PATENT OFFICE

157,281

CABINET FOR A MICROFILM RECORDER OR THE LIKE

Thomas R. Perzentka, Chicago, Ill., assignor to Bell & Howell Company, Chicago, Ill., a corporation of Illinois

Application December 24, 1947, Serial No. 143,337

Term of patent 14 years

(Cl. D33—19)

To all whom it may concern:

Be it known that I, Thomas R. Perzentka, a citizen of the United States, residing at Chicago, in the county of Cook and State of Illinois, have invented a new, original, and ornamental Design for a Cabinet for a Microfilm Recorder or the like, of which the following is a specification, reference being had to the accompanying drawing, forming a part thereof.

In the said drawing—

I claim:

The ornamental design for a cabinet for a microfilm recorder or the like, as shown.

THOMAS R. PERZENTKA.
